PROCESS OF TREATING HYDROCARBONS
IN PRESENCE OF HOT CONTACT MASSESEugene J. Houdry, Ardmore, Pa., assignor to
Houdry Process Corporation, Wilmington, Del.,
a corporation of Delaware

Application September 10, 1946, Serial No. 695,921

18 Claims. (Cl. 196—49)

1

My invention relates to the art of treating hydrocarbon material in a converter containing at least one pair of contact zones containing contact material and having between them a mixing zone or mixing chamber utilizable in the manner hereinafter described.

With the contact material in the respective mixing zones at conversion temperature, hydrocarbon material is charged continuously into the converter shell and hydrocarbon products are continuously withdrawn therefrom. In accordance with the invention, the temperature of the charge of hydrocarbon material is elevated in response to passage thereof through one of the contact zones. The converted products enter a mixing zone or mixing chamber as aforesaid where they are cooled prior to admission of all or a part thereof to the succeeding contact zone wherein the contact material, in turn, elevates the temperature of the hydrocarbon material passing therethrough. In said mixing zone, the converted products may be cooled in various ways as hereinafter described. Preferably, however, a stream of suitable hydrocarbon material is charged continuously into this mixing zone, the temperature of this hydrocarbon material being suitably lower than that of the converted products with which it mixes. Accordingly, the temperature of the incoming hydrocarbon material is elevated for subsequent conversion in the succeeding contact zone into which it passes along with some or all of the converted products as cooled by exchange of heat effected during the described mixing operation. In accordance with one aspect of the invention, the aforesaid mixing zone or mixing chamber may serve as a cooling zone.

In one application of the invention, the aforesaid contact zones comprise catalytic contact material in the presence of which a selected conversion operation may proceed as hereinafter described. In another application of the invention, the contact material in said contact zones is substantially inert in a catalytic sense and, in the presence thereof, vapors are produced, by vaporization and viscosity-breaking, from heavy hydrocarbon materials such as entire, reduced or topped crudes, residual or heavy bottoms, distillation residuums, etc., all of which contain heavy, difficultly vaporizable fractions.

In order to conduct the desired reactions or conversions, it is necessary for the aforesaid contact material in the contact zones to have heat stored therein. In accordance with an important feature of the invention, the heat which is thus

2

stored in said contact material is in excess of that required for supplying reaction heat, such excess heat being utilized for conducting the described heat-exchange operation in the mixing zone which intervenes between the contact zones. More particularly, this excess heat is utilized for elevating the temperature of hydrocarbon material passing into said mixing zone whereby such hydrocarbon material is prepared for subsequent conversion in the succeeding contact zone.

Various other objects, advantages and features of my invention will become apparent from the following detailed description.

My invention resides in the process, process steps, conversion arrangements and features of the character hereinafter described and claimed.

This application is a continuation in part of my co-pending application Serial No. 505,109, filed October 6, 1943 (now abandoned).

For an understanding of my invention and for an illustration of various arrangements with which the invention may be practiced, reference is to be had to the accompanying drawing, in which:

Figure 1 is a diagrammatic transverse sectional view showing a converter;

Fig. 2 is a similar view showing a modification of the converter;

Fig. 3 is an enlarged, partly diagrammatic, fragmentary vertical sectional view showing a modified arrangement for insuring vaporization of added charge between sections of a converter;

Fig. 4 is a vertical sectional view similar to Fig. 3 showing another modification; and

Fig. 5 is a fragmentary partly diagrammatic sectional view of a vertically disposed converter showing still another modification.

Although as hereinafter described, the invention is not to be so limited, the following detailed description relates to contact masses of the fixed bed type. Thus, referring to Fig. 1, I have shown a converter or conversion arrangement comprising three contact zones each containing contact material or contact masses *a*, *b* and *c* supported individually by suitable apertured partitions *a* and arranged in a series within a shell *3* which should be suitably insulated against heat losses by any suitable means, not shown, the pressure within the shell *3* being selected in view of the type of reaction which is conducted therein. A charge of hydrocarbon material of the character hereinafter described is sent into one end of the shell *3* by line 4 and reaction products are removed from the other end thereof by line 5. Between contact masses *a* and *b*, there is a mix-

ing zone, space or chamber *d* and, between contact masses *b* and *c*, there is a mixing zone, space or chamber *e*. Into each of such mixing zones or chambers, an additional charge of hydrocarbon material is admitted by a line *6* having valved branches *6d* and *6e* opening into chambers *d* and *e*, respectively. When the hydrocarbon material last named is either partially or entirely in the liquid phase, each of these valved branches may terminate, if desired, in a suitable nozzle *6f* by which the incoming liquid hydrocarbon material is atomized. In lieu of the nozzles *6f*, any other suitable atomizing arrangement may be utilized. Alternatively, a plurality of separate shells may be provided, each defining a contact zone and each containing contact material. These separate shells may be connected together in communicating relation and one of the aforesaid branch lines may be connected between each pair of contact zones.

When the arrangement of Fig. 1 is to be utilized for cracking the aforesaid hydrocarbon material, each of the contact masses *a*, *b* and *c*, to suitable extent, should be formed from silica-zirconia catalytic material, silica-alumina catalytic material of natural or synthetic origin or from other suitable catalytic contact material capable of effecting the desired reaction. If the catalytic material itself does not have sufficient density and heat-absorbing capacity to retain the requisite amount of heat to support the operation, it may have added thereto or mingled therewith a suitable amount of inert material having the requisite heat-absorbing characteristics as described in U. S. Letters Patent 2,414,812. With respect to the foregoing, the proportion of catalytic material to inert heat-absorbing material may range from 1:4 to 3:1 or otherwise as desirable. Further different proportions of such materials may be utilized for different contact masses. A number of suitable inert materials are mentioned in U. S. Letters Patent 2,423,835. Fused alumina and fused alumina silica (refractory material in the proportion of about 70% alumina and the remainder largely silica) have been found to be particularly suitable for this purpose.

Assuming that the temperature of the contact masses *a*, *b* and *c* has been elevated to suitable extent toward the upper level of a conversion range such, for example, as 750° F. to 1200° F. which is effective as regards catalytic cracking of hydrocarbon material of the character described immediately below and, with the valves shown in Fig. 1, positioned for on-stream operation, a charge of suitable hydrocarbon material such, for example, as heavy bottoms, which may be partly vapor, partly liquid or totally liquid, or totally vaporized gas oil may be passed continuously into the shell *3* by way of the line *4*. Simultaneously, additional charges of hydrocarbon material of the same character as that traversing the line *4*, or of other suitable character as desired, may be passed continuously into the respective chambers *d* and *e* by way of the respective branches *6d*, *6e* of line *6*. The hydrocarbon material admitted to the shell *3* by way of the line *4* passes through the contact masses *a*, *b* and *c* in succession. The additional hydrocarbon material admitted to the shell *3* by way of the branch line *6d* passes through the contact masses *b* and *c* in succession whereas the additional hydrocarbon material admitted to the shell *3* by way of the branch line *6e* passes through the single contact mass *c*. While passing through the contact masses *a*, *b* and *c*, the aforesaid hydrocarbon material from all sources

is cracked and the resulting hydrocarbon products leave the shell *3* by way of the line *5*. During the on-stream period, a definite quantity of heat is withdrawn from the contact masses to crack the hydrocarbon material passing therethrough and also to vaporize liquid phase hydrocarbon material, if any, undergoing reaction in said contact masses. The described on-stream period is terminated before the temperature of the contact masses *a*, *b* and *c* reaches the lower level of the aforesaid conversion range.

The amount of carbonaceous material deposited in or on contact material during an on-stream period is controllable within wide limits by increase or decrease in severity of reaction conditions, this applying particularly to the contact time and to the temperature of the contact material during such an on-stream period. Hence, by selecting the proper conditions, a sufficient amount of carbonaceous material may be deposited in or on the contact masses *a*, *b* and *c* during the on-stream period first named to insure production, when the carbonaceous material is burned during a regenerating operation, of a quantity of heat which is stored in said contact masses in excess of the aforesaid definite quantity of heat which is withdrawn therefrom for the purpose stated. During this regenerating operation, air or other oxidizing medium is passed through the contact masses in the direction indicated or in the opposite direction and the temperature of such air or equivalent should be 750° F. or higher in order to prevent the temperature of local areas of said contact masses from going below an acceptable combustion level.

As a result of such a regenerating operation, the temperature of the contact masses *a*, *b* and *c* is elevated toward the upper level of the described conversion range. In the event that the carbonaceous material which was deposited during the on-stream period first named is sufficient, when burned during the regenerating operation, to store in the contact masses more excess heat than required or desired, the desired proportion of the heat generated during the burning operation may be removed from the contact masses by the regenerating medium, for example, air or a mixture of air and flue gases, or by other suitable heat exchange.

In explanation of my invention, it should be noted that, ordinarily, the temperature of the hydrocarbon material traversing the line *4* is lower than the temperature of the contact mass *a*. Accordingly elevation in temperature and simultaneous cracking of such hydrocarbon material occurs as a result of passage thereof through said contact mass *a* and, at this elevated temperature, the resulting cracked hydrocarbon products pass continuously into the chamber *d*. It is a distinct feature of the invention that the temperature of the hydrocarbon material which is continuously entering the chamber *d* by way of the branch line *6d* is lower, to suitable extent, than the aforesaid elevated temperature of the aforesaid cracked hydrocarbon products entering said chamber *d* from the contact mass *a*. Accordingly, heat is transferred from said cracked products to the hydrocarbon material last named and, at an intermediate temperature lower than that of the contact mass *b*, the resulting mixture continuously enters and traverses the contact mass last named with resultant cracking and elevation in temperature thereof toward that of said contact mass *b*.

The cracked hydrocarbon products, as elevated in temperature, pass continuously from the con-

tact mass *b* and enter the chamber *e* where they mingle with the hydrocarbon material continuously entering said chamber *e* by way of the branch line *6e*, the hydrocarbon material last named being cooler, to suitable extent, than said last named cracked products. Accordingly, in the manner described with respect to the chamber *d*, heat is transferred from the cracked products last named to the hydrocarbon material last mentioned, the resulting mixture, at a temperature lower than that of the contact mass *c*, entering and traversing the latter with consequent elevation in temperature thereof toward that of said contact mass *c*. The final cracking operation occurs in the contact mass *c* and, thereafter, the cracked products pass from the shell *3* by way of the line *5*.

In view of the foregoing, it will be understood that, as regards the heat stored in the contact masses *a*, *b* and *c* as a result of the described regenerating operation, a large part thereof was withdrawn from said contact masses during the on-stream period last named in order to crack the hydrocarbon material passing therethrough. In addition, the hydrocarbon material last named withdrew from the contact masses *a* and *b* heat which in the chambers *d* and *e*, was utilized in a useful manner to heat the incoming hydrocarbon material traversing the branch lines *6d* and *6e*. By adjustment of the valves in the branch lines *6d*, *6e* or by temperature control of the hydrocarbon material traversing these branch lines, the temperature of the hydrocarbon mixtures in the respective chambers *d* and *e* may be selected so that the hydrocarbon mixtures last named withdraw desired amounts of excess heat from the respective contact masses *b* and *c* as they pass therethrough.

Accordingly, at the end of said last named on-stream period, the heat (including excess heat) previously stored in the contact masses *a*, *b* and *c* has been withdrawn therefrom as described above. During this on-stream period, carbonaceous material was again deposited in and on said contact masses. The amount of this carbonaceous material is sufficient so that, when burned, during a properly controlled subsequent regenerating operation, a quantity of heat is stored in the contact masses in excess of the endothermic reaction heat of the succeeding on-stream cracking reaction, such excess heat being utilized in the manner described for elevating the temperature of hydrocarbon material entering the chambers *d* and *e* by way of the respective branch lines *6d* and *6e*. In accordance with my invention, then, on-stream and regenerating operations of the character referred to proceed alternately for the useful purposes described in the specification.

In order to improve the octane rating of the resulting cracked products and to minimize cracking of charge and deposition of carbonaceous material in any heating equipment traversed by the hydrocarbon material prior to admission thereof to the chambers *d* and *e* by way of the respective branch lines *6d* and *6e*, it is desirable for such hydrocarbon material to be maintained under conditions such that it is substantially in the liquid phase and any prior substantial cracking thereof into lower boiling hydrocarbons of the gasoline type is avoided, the temperature of this liquid phase hydrocarbon material being at least somewhat lower than the temperature of the hydrocarbon products passing from the respective contact masses *a* and *b*, and substantially lower than that of the respective contact masses *b* and *c*.

Within the purview of the invention, the hydrocarbon material which is charged into the shell *3* either by the line *4* or by the branch lines *6d* and *6e* may be recycle stock. If so, it is desirable that fresh stock be charged into the shell *3* simultaneously with the passage of recycle stock thereto. Thus, recycle stock may be charged through the line *4* and fresh stock by way of the branch lines *6d* and *6e*. Or, if desired, recycle stock may be charged by way of the branch lines last noted and fresh stock by way of the line *4*.

For cracking of hydrocarbons, overall rates for the entire series of contact masses will range from $\frac{1}{2}:1$ (one-half volume of charge measured as liquid to one volume of catalyst per hour) up to 3:1 with flow rates in the individual sections of from $1\frac{1}{2}:1$ to 10:1.

In accordance with a detailed feature of the invention, each of the contact masses may surprise, in addition to the contact material having high heat-absorbing capacity, a catalyst having low cracking activity either with or without any suitable desulphurizing catalyst such as the oxides of nickel, cobalt, etc. on a suitable inert support. 20 Or, suitable catalytic contact material such as is formed from metals and compounds of chromium, vanadium or the like may be utilized for dehydrogenating hydrocarbons. When the contact masses are formed from catalytic contact material 25 of the character described immediately above, it will be understood that the process of my invention is operative in the manner previously described.

It was hereinbefore stated that the hydrocarbon material traversing the line *4* and the branch lines *6d*, *6e* may be totally vaporized or, alternatively, that the aforesaid hydrocarbon material may be partly liquid and partly vapor or totally liquid. If the chambers *d* and *e* receive hydrocarbon material at least partially in the liquid phase, complete or incomplete vaporization thereof may be effected in said chambers *d* and *e*, as desired. The extent of such vaporization depends upon known factors such as the efficiency of the heat-exchanging operation, the weight ratio of the materials which are subjected to heat exchange therein, the relative temperatures and character of these materials, etc.

As previously described, heat is transferred, in 50 the chambers *d* and *e*, from the hot converted products leaving the respective contact masses *a* and *b* to cooler hydrocarbon material entering said chambers by way of the respective branch lines *6d* and *6e*. The invention, however, is not 55 to be thus limited. Thus, for the purpose stated, cooler material such as steam may be admitted to said chambers *d* and *e* or, alternatively, a suitable coil, or equivalent, may be disposed in each of said chambers, each coil being traversed by cooling 60 material having temperature lower than that of the hot converted products which issue from the contact masses *a* and *b*. Accordingly, as the operation proceeds, heat is transferred from the hot converted products leaving the respective contact 65 masses *a* and *b* to the aforesaid steam or other cooling material. Hence, these converted products, as they enter the respective contact masses *b* and *c*, have temperature lower than the contact mass temperature and, during passage of said 70 converted products through said contact masses, the temperature thereof rises toward that of the contact masses.

In accordance with the invention, the arrangement of Fig. 1 may be utilized to vaporize and 75 viscosity-break heavy hydrocarbon material of

the character hereinbefore described which is introduced into the shell 3 while at least partially in the liquid phase. If so, each of the contact masses *a*, *b* and *c* should be formed entirely or substantially so from pieces of any suitable material which is substantially inert catalytically such, for example, as hereinbefore described, heat resistant quartz and quartz pebbles, fused silica, etc. The aforesaid pieces of material should have approximately uniform surface area and volume. 10 They may be of any suitable shape and the size thereof may be selected as desired. If desired, they may have approximately spherical or chunk-like configuration and the major dimension thereof may range between $\frac{1}{4}$ to $\frac{3}{4}$ of an inch, for example.

When the arrangement of Fig. 1 is to be utilized for vaporizing and viscosity-breaking purposes as described above, the contact masses *a*, *b* and *c* should have stored therein heat for effecting the subsequent on-stream reaction together with excess heat for elevating the temperature of the incoming hydrocarbon material traversing the branch lines 6*d*, 6*e*. In addition, the temperature of the contact masses should be in a range, for example, 800° F. to 1100° F., which is effective as regards vaporization and viscosity-breaking of liquid phase, heavy hydrocarbon material passed into engagement therewith. In connection with the foregoing, the upper level of the aforesaid range should be such, for example 1100° F. so, that, at the contact time employed, for example, not exceeding fifteen seconds and preferably not in excess of about five seconds, there is no substantial cracking of the hydrocarbon material into lower boiling hydrocarbons of the gasoline type, the contact time being the time required for passage through the contact masses *a*, *b* and *c* of those vapors which are introduced thereto or produced therein.

Assuming that the valves shown in Fig. 1 are positioned for on-stream operation, that the contact masses *a*, *b* and *c* have stored therein reaction and excess heat, and that the temperature thereof has been elevated toward the upper level of the described vaporizing and viscosity-breaking range, a stream of suitable material such, for example, as heavy hydrocarbon material, either partially or entirely in the liquid phase together, if desired, with suitable vapors or hydrocarbon vapors alone is charged continuously into the shell 3 by way of the line 4. Ordinarily, the temperature of this stream of material is less than that of the contact mass *a* and, hence, when it passes therethrough, there is resultant elevation in temperature thereof toward that of the contact mass from which hot vapors pass into the chamber *d*. Simultaneously, streams of material consisting either entirely or partially of heavy liquid hydrocarbon material are charged continuously into the chambers *d* and *e* by way of the respective branch lines, the temperature of the streams of material last named being substantially lower than that of the vapors issuing from the contact masses *a* and *b*.

In a manner corresponding substantially with the operation previously described, heat-exchange operations proceed in each of the chambers *d* and *e* between the hot vapors leaving the contact masses *a* and *b* and the respective streams of cooler material which are admitted to said chambers to produce partially vaporized mixtures which pass into the respective contact masses *b* and *c* where the liquid portions of the charge are vaporized and converted, i. e. viscosity-broken.

Provided that the temperature of the contact masses *a*, *b* and *c* is within the proper range and that the contact time, as determined by known factors, is sufficiently short as hereinbefore described, the heat transferred, during the operation described above, from the contact masses to the liquid phase hydrocarbon material effectively vaporizes and viscosity-breaks the difficulty vaporized components thereof. As a result, there is formed distillate hydrocarbon material which is principally higher boiling than gasoline, this material passing from the shell 3 by way of the line 5.

In accordance with the invention, the temperature and/or rate of flow of the hydrocarbon material traversing said branch lines 6*d*, 6*e* may be varied to change the temperature of the aforesaid mixtures in the respective chambers *d* and *e* in a desired manner. To this end, suitable means, not shown, may be provided for jointly or individually varying the temperature of the material entering the shell 3 by way of the branch lines 6*d*, 6*e*. Or, the valves in the respective branch lines may be adjusted to vary the rate of flow of such material. Accordingly, by controls suitably effected, the operating temperatures of the contact masses *b* and *c* may be related to each other and also to the operating temperature of the contact mass *a* in a desired manner. Preferably but not necessarily, by the aforesaid controls or equivalent, the temperatures of all of the contact masses are so maintained that, at any selected time, they are approximately at the same level.

It has been hereinbefore stated that the temperature of the hydrocarbon material charged into the chambers *d* and *e* by the respective branch lines 6*d* and 6*e* is lower to suitable extent than the vapors passing into said chambers from the respective contact masses *a* and *b*. In general, the temperature of such hydrocarbon material may be substantially lower, for example, 75° F. to 125° F., than that of the aforesaid vapors. In any event, it is important for the hydrocarbon material to be introduced into the chambers *d* and *e* under conditions such that approximately the entire quantity of excess heat in the contact masses is absorbed thereby.

There may be any desired number of contact masses in the series and the depth of these contact masses may be such as is suitable and desirable, for example, from one foot to six feet, more or less. The depth of individual contact masses may differ so as to provide equivalent or modified times of contact. Thus, when additional charge is admitted to a chamber *d* or *e* with no withdrawal of products therefrom, the succeeding contact mass may be of increased depth or 50 volume to provide equivalency of contact with the preceding contact mass. Also, one or more of the contact masses may be of increased depth or volume to compensate for increased refractoriness of partially converted charging stock.

It is desirable, in connection with the invention as herein described, for the cycle of operation to be relatively short. Preferably, the duration of each on-stream period should not exceed about thirty minutes and, usually, the duration of each regenerating period is about the same as the on-stream period.

In a preferred application of the invention, but not necessarily, there is a balance, except for heat losses from the equipment, as by radiation, between the heat stored in the contact masses at the start of an on-stream period and the heat withdrawn from said contact masses for effect-

ing the on-stream reaction and elevating the temperature of the additional charges of material, this balance being controlled by the extent of deposition of carbonaceous material which, in turn, is readily controlled, for example, by adjusting the quantity of feed, the rate of flow to the various contact masses or of other conditions affecting the extent of conversion of the charged hydrocarbon material in carbonaceous material.

In Fig. 2, I have shown an arrangement which, generally, is similar to Fig. 1 and, to common parts, the same reference characters have been applied. The variation in Fig. 2 consists in the provision of outlet line 7 with valved branches 7d and 7e by which a portion of the reaction products may be withdrawn from one or both of the chambers or spaces d and e. Line 7 may join outlet line 5 if desired and as indicated. With the arrangement of Fig. 2, products may be withdrawn from the chambers d and e by way of the respective branch lines 7d and 7e in an amount approximately the same as the amount of the material which is admitted thereto by the respective branch lines 6d and 6e. With this type of operation, approximately the same amount of material passes through each of the contact masses.

It will be understood that the arrangement of Fig. 2 may be utilized in accordance with various applications of the invention as hereinbefore described with respect to Fig. 1. That is, the contact masses shown in Fig. 2 may be catalytically active or inert, all as hereinbefore described with respect to Fig. 1.

As hereinbefore stated, liquid phase material or liquid charges may be admitted to the shell 3 including the chambers d, e thereof. It was also stated with respect to those forms of the invention wherein catalytic contact material is utilized that, in said chambers d and e, the operation may be alternative, namely, there may be either partial vaporization or complete vaporization of the liquid phase material. When complete vaporization is desired, provision should be made to insure completion of that operation before any of the liquid charge reaches the subsequent contact masses and any charge not completely vaporized should be removed or kept out of contact with the active contact material. Accordingly, a vapor space or chamber of adequate size may be provided between adjacent contact masses to insure complete vaporization, or means to intercept unvaporized charge may be provided. When the available vapors leaving a contact mass are passed countercurrently to additional charge entering as a fine spray or in atomized condition with vapor to liquid ratio of 6:1 by volume (liquid basis), vaporization can be effected in a space up to four feet in length. More vapor space may be needed as the proportion of liquid is increased, as of the order of 6 to 8 feet or more for a vapor-liquid ratio of 3:1.

Figs. 3 to 5 of the drawing illustrate ways to utilize restricted vapor space between sections of contact mass and to prevent unvaporized charge from contact with catalyst. In Fig. 3 contact mass b is protected against impingement of liquid particles issuing from feed line 6' through one or more spray nozzles 8' by interposition of a layer 9 of highly porous inert material in the form of grains, fragments or molded pieces such for example as the carrier material disclosed in U. S. Patent No. 1,818,403 issued August 11, 1931 to Alfred Joseph. Layer 9 is of suitable thickness, as 4 to 18 inches for exam-

ple, depending upon the extent of the vapor space into which nozzles 8' discharge and the quantity and character of liquid supplied by the latter. This porous layer will retain the liquid particles until vaporization on extended surfaces takes place. A part of the vapors issuing from contact mass a may be withdrawn by valved line 7'; a baffle 10 in the form of reticulated material or a perforated plate may be mounted if desired so as to divert a part of the reaction products from mass a toward outlet 7' and thus prevent or minimize the mingling of additional charge from feed line 6' with the reaction products withdrawn by line 7'.

In Fig. 4, reaction products from mass a pass into a chamber 11 having a centrally disposed outlet 12a in a dished baffle plate 12 which serves to constrict such products as they move toward mass b. Outlet 12a is preferably in the form of venturi nozzle into which, or adjacent to which, is located spray nozzle 8'' for additional charge from line 6''. The mingled reaction products and additional charge impinge against an inwardly dished baffle member 13 which directs the mixture outwardly and back toward baffle 12 until the mixture passes around the outer edges of baffle member 13 into chamber 14 and thence into the next contact mass b. This arrangement extends the path of flow of the mingled reaction products and atomized charge and gives the latter time to become vaporized before entering mass b. Moreover, reaction products entirely free of any additional charge from line 6'' can be withdrawn from chamber 11 by line 7''.

Steam or other vaporizing medium may be mingled with charge issuing from nozzle 8'' or steam may be added before or as the charge impinges on baffle 13 (by means not shown) to assist in vaporization of liquid film on the baffle.

Fig. 5 shows a fragmentary section of a vertically disposed converter wherein reaction products from contact mass a pass into a chamber against additional liquid charge issuing countercurrently from a series of nozzles 16 supplied by line 16. Unvaporized liquid is intercepted by a layer of inert porous material 19 of the same type as used for layer 9 of Fig. 3. Any liquid which makes its way through layer 19 is caught by a slanting plate 20 mounted therebelow equipped with a valved drain pipe 20a. Plate 20 has a multiplicity of vents provided by short pipes 20b extending above the upper surface of the plate, these pipes having their open ends bent over toward plate 20 to exclude any liquid dropping from porous layer 19 but to permit passage of gases and vapors to chamber 21 below plate 20 and thence into contact mass b. Any burnable deposits which accumulate on porous mass 9 in Fig. 3 or on mass 19 of Fig. 5 are burned away during subsequent regenerating operations with little if any effect upon the cycle of operation.

Arrangements of the character described above may be utilized when total vaporization is to be effected in a chamber between adjacent contact masses. However, it shall be understood that, except as set forth in the appended claims, there is to be no restriction of the invention to an operation involving total vaporization in a chamber as described above.

It is a feature of the invention that, as regards the various aspects of the invention, the material undergoing conversion in the series of contact masses is subjected to undulating or oscillating temperature conditions as it passes through

said contact masses. Thus, the material rises in temperature as it passes through each contact mass and falls in temperature in the chamber between each pair of contact masses. As stated, the converter of the invention may comprise a desired number of contact masses. If the number is small, as two to four, and if comparatively large amounts of additional charge are introduced between the contact masses, severe conditions may be selected to effect substantial conversion and to produce comparatively large quantities of deposited carbonaceous material. Under these circumstances, the temperature swing within the mass (difference between the average contact mass temperatures at the beginning and end, respectively, of the on-stream periods) may be wide, as up to 250° F. However, when the same extent of conversion is desired utilizing more contact masses, a greater number of smaller additions of additional charge can be made, and accordingly, less severe operating conditions may be required for the same total yield, thereby giving smaller quantities of carbonaceous material and narrow temperature swings (as from 40° F. to 120° F.) commensurate with the smaller increments of conversion in each mass. Operation of an increased number of contact masses is not limited to maintaining narrower temperature swings for, obviously, severe operating conditions may be employed to attain maximum conversion of a maximum quantity of charge.

In accordance with present preferred practice, the same type of conversion occurs in all of the contact masses disposed within a converter shell and, preferably, the temperature range is substantially the same for all of the contact masses. However, the invention is not to be thus limited since, in a broader aspect thereof, the conversion may be of different character in different contact masses and the temperature range as regards different contact masses may be such as is suitable for the different operations.

Besides the inventive features hereinbefore described, conversion of hydrocarbon material in accordance with my invention is desirable because reducing the size of the still or other auxiliary heating apparatus. This is true principally by reason of the fact that the hydrocarbon material traversing the branch lines 6d and 6e, before conversion, is subjected to temperature elevation in the converter. When liquid hydrocarbon material traverses these branch lines, it may be heated to such extent as desirable and it may be entirely unheated if free-flowing at room temperature.

It was hereinbefore stated, with respect to various forms of the invention that, ordinarily, the material entering the shell 3 by way of the line 4 has temperature lower than that of the contact mass a. Should the temperature of this material be higher than that of said contact mass a, it will be recognized that excess heat is not withdrawn therefrom. However, under the circumstances last recited, hydrocarbon material, by another branch of the line 6, may be charged into the chamber in advance of the contact mass a. If the temperature of this hydrocarbon material is suitably lower than that of said higher temperature material, a resulting mixture is obtained having temperature lower than that of the contact mass a and this mixture withdraws heat from said contact mass a upon passage therethrough.

In the preceding part of this specification, the specific description relates to converters of the fixed bed type. However, the invention is not to be so limited. As well, from some of its broader aspects, the invention relates to converter arrangements wherein the contact material, as the reaction proceeds, may move through the several contact zones, either separately through each zone or successively through several of such zones, a mixing chamber being disposed between each pair of said zones for the purpose described.

For purposes of explanation and without limitation of the invention, the following examples 15 are included as a part of this specification.

Example I

A three section converter conforming to that shown in Fig. 2 with contact masses two feet in depth composed 50% by volume of active adsorptive cracking catalyst in pelleted form and 50% by volume of fused alumina and silica grain of approximately the same size as the catalyst pellets, the latter being synthetic silica-alumina, was utilized for the conversion of East Texas gas oil (boiling range 420-760° F.). At one end vaporized fresh charge at about 800° F. was admitted to the converter at an overall rate 20 based on total volume of catalyst of 3:4 (liquid volume of charge per volume of catalyst per hour), the rate for each section of catalyst being 9:4. Product withdrawn from the opposite end of the converter was fractionated and unconverted recycle stock was utilized as additional charge between the sections of the contact masses. Such additional charge having about the same boiling range as the fresh charge to the converter was sprayed into each of the vapor spaces d and e (12 feet long in this instance) counter-current to the reaction products issuing from contact masses a and b. The quantity of additional charge admitted to each vapor space 25 was approximately $\frac{1}{3}$ of the original charge to the converter. From each of the vapor spaces there was withdrawn approximately $\frac{1}{3}$ of the reaction products issuing from the preceding contact mass, such withdrawals being added to the reaction products withdrawn from the said opposite end of the converter. On-stream periods were 10 minutes, followed by purging and burning or regenerating periods totalling 30 minutes, three converters being utilized in known manner to maintain continuous production. During the burning phase of regeneration (approximately 10 minutes) air preheated 35 to about 800° F. was admitted at one end of the converter, and additional air was admitted between the sections of contact mass. Throughout the cycle no part of any of the contact masses reached a temperature in excess of about 1100° F., the average contact mass temperature at the beginning of on-stream periods being 40 about 940° F. and at the end of these periods about 845° F. Thus the average on-stream temperature was approximately 100 degrees below the average regeneration temperature. The yield of condensed motor gasoline was approximately 47% by volume of the charge. Approximately 75% of the heat of combustion of catalyst deposit, exclusive of losses through fumes and converter walls, was utilized to supply heat 45 of reaction and to prepare the charges for conversion.

Example II

The converter was made up of three sections in all respects similar to the converter in Example I except that the vapor space between adjacent sections of contact mass was six feet instead of 12 feet. The contact mass was similar to that set forth in Example I. The same feed stock for conversion was utilized and the same general method of operation. The fresh feed was sent into one end of the converter at an overall charge rate based on total quantity of catalyst of 1:1 (liquid volume of charge per volume of catalyst per hour) and additional feed stock in the form of recycle material was sprayed into the vapor spaces *d* and *e*, the quantity added to each space being about $\frac{1}{6}$ of the quantity of fresh feed being charged to the converter. From the vapor space *d* there was withdrawn about 14% of the products issuing from contact mass *a* and from the second vapor space *e* about 27% of products were withdrawn. The average contact mass temperature at the beginning of the on-stream periods was about 920° F. and at the end of the on-stream period about 845° F., giving an average spread of about 75° F. The yield of condensed motor gasoline was approximately 35% by volume of the charge of fresh feed.

Example III

The operation was conducted in a three sectional converter conforming to that shown in Fig. 2 with six foot vapor spaces between contact masses. The general method of operation was as in Examples I and II except that the charge sent into one end of the converter was a mixture of recycle stock from the fractionator and fresh East Texas gas oil of the same boiling range as in Example I, the ratio of recycle to fresh charge being 2:1. The mixture was charged to the converter at an overall feed rate of about 1:1 (liquid volume of charge per volume of catalyst per hour) based on the quantity of catalyst in the three contact masses. The additional charge between sections was fresh East Texas gas oil, the additions sprayed into vapor spaces *d* and *e* being each approximately $\frac{1}{6}$ of the quantity of mixed feed charged to the converter. Withdrawals from the two vapor spaces were approximately $\frac{1}{6}$ of the products from each preceding contact mass. The average catalyst temperature at the beginning of the on-stream period was 970° F. and at the end of the on-stream period about 870° F., giving an average spread of about 100° F. The yield of motor gasoline based on total fresh East Texas charge to the operation was about 52%.

Example IV

The operation was conducted in a two section converter of the type indicated in Fig. 1, each contact mass section being four feet in depth with a six foot central vapor space between the two sections. The contact mass was a 50-50 blend of active adsorptive silica-alumina cracking catalyst in pelleted form and fused alumina and silica grain of approximately the same size. The charging stock was East Texas gas oil of the boiling range of Example I. Additional charge was sent into the converter between the two contact masses but there was no withdrawal of products from the central vapor space. Fresh gas oil was charged partly to one end of the converter at a 0.4:1 rate along with recycle stock which was charged at a 1.6:1 rate, both rates

being based on total amount of catalyst in both masses. The additional charge to the central vapor space was fresh gas oil in an amount approximately 20% by volume of the total feed to the first section. For regeneration the regenerating medium was fed to the first section and withdrawal of fumes was from the opposite end of the converter. The average temperature of the contact mass at the beginning of the on-stream period was 995° F. and at the end of the on-stream period 885° F., giving an average temperature spread of about 110°. The yield of gasoline of 10 Reid vapor pressure was 65% by volume of the fresh charge. The gas produced amounted to 28% by weight of fresh charge and had the following composition by weight.

	Per cent by weight
Hydrogen	0.5
20 Methane	7.0
Ethane	4.3
Ethylene	4.8
25 Propane	10.3
Propene	21.1
25 Isobutane	19.2
N-butane	4.6
Isobutylene	4.1
N-butene	10.1
Isopentane	9.0
30 N-pentanes	0.6
Pentenes	4.4
	100.0

Example V

The operation was conducted in a converter having four sections of contact mass, the depth of mass in each section being two feet with vapor spaces between adjacent sections of four feet. As in the other examples the contact masses were 50-50 blends of active silica-alumina cracking catalyst and fused alumina and silica grain. The charge to the first section of the converter was unconverted recycle stock from the fractionator (boiling range approximately 420° F. to 750° F.). The rate of charge to the first section was 1 1/2:1 (liquid volume of charge per volume of catalyst per hour) based on total amount of catalyst in all four sections. Additions of charging stock were made in the three vapor spaces between adjacent sections of catalyst, this additional charge being fresh East Texas gas oil at about 300° F., each such addition being approximately 20% by volume of the quantity of recycle stock charged to the first section. Products were withdrawn from the vapor spaces after each of the first three sections, the quantity withdrawn being approximately equal in weight to the fresh charge sent into each such vapor space. The operating periods were ten minutes on-stream and 20 minutes in regeneration. During regeneration fumes were vented from the central vapor space and from both ends of the converter while the regenerating medium, air, was admitted at 940° F. to the other two vapor spaces. The average contact mass temperature at the beginning of the on-stream operation was about 975° F. and at the end of the on-stream operation about 860° F., so that the average on-stream temperature was approximately 115° F. below the average regenerating temperature. The yield of motor gasoline (of about 410° F. end point) was about 70% by volume of the fresh East Texas gas oil charged, the gasoline having a Reid vapor pressure of 10 lbs. and octane rating (C. F. R. research method)

15

of 91. In this instance the gasoline yield represented the total liquid recovery from the operation. Additional liquid could have been produced by polymerization and alkylation from the remaining fixed gases which were high in unsaturates and iso-compounds.

Example VI

A converter having three separate contact masses formed from pieces of fused alumina and silica each having a major transverse dimension of about $\frac{1}{4}$ to $\frac{1}{2}$ of an inch was operated as follows: Cracked hydrocarbon vapors including cracked gasoline and fixed gas having temperature of approximately 935° F. were charged into one end of the converter under pressure of 23 pounds per square inch and at a rate, compared with the total volume of contact material in said converter, of 2.1 volumes (liquid basis) per hour. Into the space in advance of each contact mass, there was admitted a stream of a heavy oil, together with 15% of steam by weight, which was the 43% through 100% cut of East Texas crude having the following boiling range characteristics as determined by vacuum assay: 5% at 486° F., 50% at 663° F. and 89% at 1005° F. The charging rate of each stream of heavy oil, compared with the total volume of contact material in said converter, was 0.4 volume (liquid basis) per hour. At the beginning of the on-stream period, the following temperature conditions existed with respect to the contact masses: The first contact mass at the respective entrance and exit sides thereof had temperature of 1000° F. and 910° F.; the second contact mass at the respective entrance and exit sides thereof had temperature of 950° F. and 945° F.; and the third contact mass at the mid-point and exit sides thereof had temperature of 920° F. At the termination of the on-stream period, the following temperature conditions existed with respect to said contact masses: The first contact mass at the respective entrance and exit sides thereof had temperature of 865° F. and 870° F.; the second contact mass at the respective entrance and exit sides thereof had temperature of 850° F. and 855° F.; and the third contact mass at the respective mid-point and exit sides thereof had temperature of 860° F. and 870° F. The heavy oil, while substantially in the liquid phase, was admitted to each of the aforesaid spaces at a temperature of 600° F. By action thereon of the stream of hot vapors, the heavy oil was vaporized to some extent and, therefore, in each space, a partially vaporized mixture was produced having temperature lower than that of the succeeding contact mass. Hence, a partially vaporized mixture was admitted to each contact mass with resultant vaporization and viscosity-breaking of the liquid phase material, the totally vaporized mixture leaving each contact mass at temperature which had been elevated toward that of the contact mass. The contact time of the vapors in the first, second and third contact masses was, respectively, 2.8 seconds, 2.3 seconds and 1.9 seconds.

Of the heavy East Texas bottoms admitted in advance of each contact mass, more than 96% by weight was discharged from the converter as vaporized material admixed with the cracked vapors which were admitted to said converter. The remainder, less than 4% by weight of said heavy East Texas bottoms, was retained in the contact mass as a deposit of coke or carbonaceous material containing substantially all of the inorganic salts and other non-volatile inorganic

16

material present in said bottoms as well as the coke or carbonaceous material resulting from conversion of the difficultly vaporizable components of the bottoms.

Example VII

A light gas oil was passed through a heater in order to produce vapors which were admitted to a cracking converter at a temperature of 850° F. The A. P. I. gravity of this light gas oil was 29.3, the initial boiling point was 480° F., the 50% boiling point was 558° F., and the 95% boiling point was 723° F. The vaporized gas oil was thus charged to the cracking converter under pressure of 23 pounds per square inch and at a rate, compared with the total volume of contact material in the cracking converter, of 0.75 volume (liquid basis) per hour. The cracking converter had six separate contact masses formed from equal parts of pieces of fused alumina and silica, as hereinbefore described, and pieces of catalytic contact material having an activity index of 25 as expressed in terms of the standard test described in "Laboratory Method for Determining the Activity of Cracking Catalysts" by J. Alexander and H. G. Shimp, page R537, National Petroleum News, Technical Section, August 2, 1944. The respective contact masses were formed from progressively increasing amounts of contact material. Thus, the contact mass first engaged by the aforesaid vaporized material was formed from 4.5 liters of contact material and the succeeding contact masses were formed, respectively, from 5.3 liters, 6.2 liters, 7.3 liters, 8.5 liters and 10.0 liters of contact material.

Into the space in advance of each contact mass, with the exception of the first (that contact mass which is first engaged by the vaporized gas oil), there was admitted, together with 10% of steam by weight, a heavy gas oil in the form of a bottom fraction from a fractionating zone. The charging rates of the respective streams of heavy gas oil, compared with the total volume of contact material in the cracking converter, which were admitted in advance of the second, third, fourth, fifth and sixth contact masses were, respectively, 0.11, 0.13, 0.15, 0.17 and 0.19 volume (liquid basis) per hour. The A. P. I. gravity of this heavy gas oil was 23.9, the initial boiling point was 476° F., the 50% boiling point was 640° F., and the 93% boiling point was 762° F.

This heavy gas oil, while in the liquid phase, was admitted into each of the aforesaid spaces, except the first, at a temperature of 275° F. and, by action thereon of the streams of vaporized material, it was substantially completely vaporized. Therefore, in each of said last named spaces, a vaporized mixture was produced having temperature lower than that of the succeeding contact mass. From each space last referred to, then, a vaporized mixture passed into the succeeding contact mass with resultant elevation in temperature and conversion thereof into hydrocarbon products. During the on-stream period, the average temperature of the vapors entering and leaving each contact mass was substantially as follows: First contact mass, 850° F. and 950° F.; second contact mass 852° F. and 940° F.; third contact mass, 860° F. and 915° F.; fourth contact mass, 865° F. and 975° F.; fifth contact mass 870° F. and 940° F.; and sixth contact mass, 870° F. and 1000° F.

Example VIII

A four section converter was employed wherein the depth of each of the first and second contact

masses was two feet and that of the third and fourth contact masses was two and one half feet, each of the contact masses being composed, by volume, of one-third active cracking catalyst and two-thirds of fused alumina and silica grain. The active cracking catalyst was formed from low alkali, silica-alumina material and the activity indices, as expressed in terms of the standard test described in "Laboratory Method for Determining the Activity of Cracking Catalysts," by J. Alexander and H. G. Shimp, page R537, National Petroleum News, Technical Section, August 2, 1944, of the first, second, third and fourth contact masses were, respectively, 28.7, 29.6, 34.0 and 35.8. The depth of the chamber between each pair of contact masses was two feet and seven inches.

A hydrocarbon vapor phase mixture, composed of a 42-88% fraction (32.1° A. P. I. gravity) of East Texas crude at a charging rate of 0.85 volume (liquid basis) per hour per total volume of the active catalyst material, was admitted at a temperature of 825° F. in the presence of steam, amounting to 10% by weight of the fresh feed hydrocarbon mixture, to that end of the converter containing the first contact mass. Into the space in advance of each of the second, third and fourth contact masses, there was admitted a side stream of hydrocarbons composed of recycle stock (32.0° A. P. I. gravity and boiling within the approximate range of 460° F. to 650° F.) derived from the aforesaid 42-88% fraction of East Texas crude, the rate of charge for each side stream being approximately one third of the total side stream charge which was 0.75 volume (liquid basis) per hour per total volume of the active catalyst material in the converter.

During the on-stream period, the average temperatures of the contact masses in the order named and approximately at the respective exit ends thereof were 885° F., 920° F., 935° F. and 938° F. The temperatures of the hot vapors, upon passage thereof from each of said contact masses in the order named, averaged approximately 870° F., 905° F., 890° F. and 910° F. respectively during the on-stream period. The side streams, while substantially in the liquid phase, were admitted into each of the aforesaid spaces at temperatures of 430° F., 370° F. and 390° F., respectively. Heat was exchanged between the vapors and liquid material with resultant vaporization of the latter. The vaporized mixtures had average temperatures of approximately 790° F., 810° F. and 830° F. upon passage thereof into the respective second, third and fourth contact masses during the on-stream period.

The operation above described yielded 48.4% (by volume of the charge) of gasoline with a gravity of 57.5° A. P. I. The gasoline had an octane rating of 82.9 when tested by the CFR-Motor method and 93.0 when tested by the CFR-Research method.

While the invention has been described with respect to certain particular preferred examples which give satisfactory results, it will be understood by those skilled in the art, after understanding the invention, that various changes and modifications may be made without departing from the spirit and scope of the invention and it is intended, therefore, in the appended claims to cover all such changes and modifications.

I claim as my invention:

1. The process of treating hydrocarbon material in the presence of catalytic contact material adapted to promote a cracking operation con-

ducted in each of a pair of contact zones having a cooling zone between them and thereafter to be subjected to a regenerating operation, the steps which comprise conducting a cracking operation of the character described below in the presence of such catalytic contact material with resultant deposition thereon of an amount of carbonaceous material which, when burned during the subsequent regenerating operation, stores in the catalytic contact material an amount of heat substantially in excess of that required for effecting an on-stream cracking operation in the contact zones, burning the deposited carbonaceous material from the catalytic contact material with resultant storage therein of an amount of heat as specified above, causing hydrocarbon material having temperature lower than that of the catalytic contact material in one contact zone to pass therethrough to remove stored excess heat therefrom with resultant elevation in temperature of the hydrocarbon material and substantial conversion thereof into cracked products which enter said cooling zone at such elevated temperature, introducing into said cooling zone a medium having temperature lower than that of said cracked products, heat being exchanged between said cracked products and said medium to lower the temperature of the cracked products to a desired level below that of the catalytic contact material in the other contact zone, and passing at least a portion of said cracked products, as the operation proceeds, into said last named contact zone with resultant elevation in temperature thereof, further substantial cracking conversion thereof and removal of stored excess heat from said last named contact zone.

2. The process of treating hydrocarbon material in the presence of contact material adapted to affect conversion endothermically conducted in each of a pair of contact zones having a mixing zone between them and thereafter to be subjected to a regenerating operation, the steps which comprise conducting a conversion operation of the character described below in the presence of such contact material with resultant deposition thereon of an amount of carbonaceous material which, when burned during the subsequent regenerating operation, stores in the contact material an amount of heat substantially in excess of that required for effecting on-stream conversion in the contact zones, burning the deposited carbonaceous material from the contact material with resultant storage therein of an amount of heat as specified above, causing hydrocarbon material having temperature lower than that of the contact material in one contact zone to pass therethrough to remove stored excess heat therefrom with resultant elevation in temperature of the hydrocarbon material and substantial conversion thereof into hydrocarbon products which enter said mixing zone at such elevated temperature, introducing into said mixing zone hydrocarbon material having temperature lower than that of said hydrocarbon products, heat being exchanged between said hydrocarbon products and said hydrocarbon material to produce a hydrocarbon mixture having temperature lower than that of the contact material in the other contact zone, and passing at least a portion of said hydrocarbon mixture, as the operation proceeds, into said last named contact zone with resultant elevation in temperature thereof, substantial conversion thereof and removal of stored excess heat from said last named contact zone.

3. The process of claim 2 in which the contact material is a mixture formed from solid pieces of catalyst and inert material having relatively high heat-absorbing capacity.

4. The process of treating hydrocarbon material in the presence of contact material adapted to affect conversion endothermically conducted in each of a pair of contact zones having a mixing zone between them and thereafter to be subjected to a regenerating operation, the steps which comprise conducting a conversion operation of the character described below in the presence of such contact material with resultant deposition thereon of an amount of carbonaceous material which, when burned during the subsequent regenerating operation, stores in the contact material an amount of heat substantially in excess of that required for effecting on-stream conversion in the contact zones, burning the deposited carbonaceous material from the contact material with resultant storage therein of an amount of heat as specified above, causing hydrocarbon material having temperature lower than that of the contact material in one contact zone to pass therethrough to remove stored excess heat therefrom with resultant elevation in temperature of the hydrocarbon material and substantial conversion thereof into hydrocarbon products which enter said mixing zone at such elevated temperature, introducing into said mixing zone hydrocarbon material at least partially in the liquid phase and having temperature lower than that of said hydrocarbon products, heat being exchanged between said hydrocarbon products and said hydrocarbon material to produce a hydrocarbon mixture having temperature lower than that of the contact material in the other contact zone, and passing at least a portion of said hydrocarbon mixture, as the operation proceeds, into said last named contact zone with resultant elevation in temperature thereof, substantial conversion thereof and removal of stored excess heat from said last named contact zone.

5. The process of claim 4 in which said hydrocarbon mixture is in totally vaporized condition prior to passage thereof into said last named contact zone.

6. The process of claim 4 in which said hydrocarbon mixture is only partially vaporized prior to passage thereof into said last named contact zone.

7. The process of treating hydrocarbon material in the presence of contact material adapted to affect conversion endothermically conducted in each of a pair of contact zones having a mixing zone between them and thereafter to be subjected to a regenerating operation, the steps which comprise conducting a conversion operation of the character described below in the presence of such contact material with resultant deposition thereon of an amount of carbonaceous material which, when burned during the subsequent regenerating operation, stores in the contact material an amount of heat substantially in excess of that required for effecting on-stream conversion in the contact zones, burning the deposited carbonaceous material from the contact material with resultant storage therein of an amount of heat as specified above, causing hydrocarbon material having temperature lower than that of the contact material in one contact zone to pass therethrough to remove stored excess heat therefrom with resultant elevation in temperature of the hydrocarbon material and substantial conversion thereof into hydrocarbon

products which enter said mixing zone at such elevated temperature, introducing into said mixing zone hydrocarbon material having temperature lower than that of said hydrocarbon products, heat being exchanged between said hydrocarbon products and said hydrocarbon material to produce a hydrocarbon mixture having temperature lower than that of the contact material in the other contact zone, and passing at least a portion of said hydrocarbon mixture, as the operation proceeds, into said last named contact zone with resultant elevation in temperature thereof, substantial conversion thereof and removal of stored excess heat from said last named contact zone, the temperature of the contact material in said contact zones decreasing at approximately the same rate during continuance of the conversion period.

8. Process of effecting hydrocarbon conversion reactions in vapor phase by catalysis in a cycle of on-stream and regenerating reactions through the action of catalytic material mingled with heat absorbing material in a composite contact mass, the process comprising effecting the conversion of the charge by stage catalysis in a series of said composite contact masses maintained at temperatures in excess of 750° F., removing a portion of the products of conversion after each of said masses, mingling additional charge in liquid phase with the remaining products before they enter the next contact mass, and controlling operating conditions to produce sufficient burnable deposit on each mass during on-stream reactions to store sufficient heat in each mass during regeneration by burning of said deposit to supply the heat of reaction of the subsequent on-stream reaction as well as sensible heat and heat of vaporization for additional charge when supplied intermediate said contact masses.

40 9. Process of effecting hydrocarbon conversion reactions by catalysis in a cycle of on-stream and regenerating reactions through the action of catalytic material mingled with heat absorbing material in a composite contact mass, the process comprising effecting the conversion of the charge at least partially in vapor phase by stage catalysis in a series of said composite contact masses maintained at temperatures in excess of 750° F., removing a portion of the products of conversion issuing from at least one of said contact masses, mingling atomized liquid charging stock with the remainder of the products, utilizing the heat of said remaining products to vaporize atomized liquid so added to said charge, and controlling operating conditions to produce sufficient burnable deposit on said masses during on-stream reactions to store sufficient heat in said masses during regenerating by burning of said deposit to supply heat of reaction and heat of vaporization of additional charging stock in subsequent on-stream reactions.

10. Process of effecting hydrocarbon conversion reactions by catalysis in a cycle of on-stream and regenerating reactions through the action of catalytic material mingled with heat absorbing material in a composite contact mass, the process comprising effecting the conversion of substantially vapor phase charge by stage catalysis in a series of said composite contact masses maintained at temperatures in excess of 750° F., mingling additional charge comprising liquid in atomized condition with products leaving one of said contact masses before the products enter the next contact mass, and controlling operating conditions to deposit sufficient burn-

able deposit on each mass during on-stream reactions to store sufficient heat in each mass during regeneration by burning of said deposit to supply the heat of reaction of the subsequent on-stream reaction as well as sensible heat and heat of vaporization for additional charge when supplied intermediate said contact masses.

11. In use of contact mass alternately on-stream to effect conversion of a hydrocarbon charge which produces burnable deposit on said mass and in regeneration by burning of said deposit wherein heat required for said conversion and supplied by said mass is stored in the latter during said regeneration, the process comprising effecting such a cycle in a plurality of separate contact masses through which a hot stream of said charge passes in succession while being maintained at a temperature suitable for effecting the same type of conversion in each mass, effecting said cycle under conditions such that the quantity of heat stored in said masses during regeneration is in excess of that required for effecting the on-stream reaction, and admitting additional and comparatively cool hydrocarbon charge to said stream during its movement between said least one pair of adjacent contact masses to utilize excess stored heat by transferring sensible heat of said stream to said additional charge to heat the latter.

12. Process according to claim 11 wherein the charge passed serially through the separate masses and the additional charge are hydrocarbons heavier than gasoline and the masses comprise active cracking catalyst maintained at cracking temperature.

13. In the operation of a sectional catalytic converter providing a series of separate contact masses in an operating cycle of alternating regenerating and on-stream periods wherein exothermic heat resulting from regeneration is stored within said masses to be released to the succeeding on-stream processes, the process of utilizing excess heat so stored and of maintaining said masses at desired operating temperatures during said on-stream periods comprising the steps of passing a hydrocarbon stream into and through the first of said masses with resultant withdrawal of heat therefrom, the resulting products and resulting partially converted charge passing serially through the balance of said masses, and mingling with reaction products from one mass comparatively cool additional hydrocarbon charge in quantity controlled to maintain the temperature of the next succeeding contact mass at approximately the level obtaining within the aforesaid one mass.

14. In the operation of a sectional catalytic converter providing a series of separate contact masses in an operating cycle of alternating regenerating and on-stream periods wherein exothermic heat resulting from regeneration is stored within said masses to be released to the succeeding on-stream processes, the process of utilizing excess heat so stored and of maintaining said masses at desired operating temperatures during said on-stream periods comprising the steps of passing a hydrocarbon stream into and through the first of said masses with resultant withdrawal of heat therefrom, the resulting products and resulting partially converted charge passing serially through the balance of said masses, mingling with reaction products from one mass comparatively cool additional hydrocarbon charge in quantity controlled to maintain the temperature of the next

succeeding contact mass at approximately the level obtaining within the mass from which the product containing stream has issued, and withdrawing a portion of said stream of products and partially converted charge from the converter prior to said mingling of additional charge.

15. In effecting hydrocarbon conversion reactions in the presence of a series of separate contact masses employed in an operating cycle of alternating regenerating and on-stream periods wherein exothermic heat resulting from regeneration is stored within said masses to be released to said reactions during the succeeding on-stream periods, the process of utilizing excess heat so stored and of maintaining said masses at desired operating temperatures during said on-stream period comprising the steps of passing a stream of hot vaporized ordinarily liquid on-stream hydrocarbon charge into and through the first of said masses, the resulting products and partially converted charge passing serially through the remainder of said masses to withdraw heat from each of them, mingling with reaction products from one mass additional hydrocarbon charge comprising comparatively cool liquid to effect vaporization of the latter by utilization of sensible heat content of said products, and controlling the quantity of additional charge so added to maintain the next succeeding contact mass at conversion temperature at least approximating that obtaining within the aforesaid one mass.

16. In use of a contact mass alternately on-stream to effect conversion of a hydrocarbon charge which produces burnable deposit on said mass and in regeneration by burning of said deposit wherein heat required for said conversion and supplied by said mass is stored in the latter during said regeneration, the process comprising effecting such a cycle in a plurality of separate contact masses through which a hot stream of said charge passes in succession, while being maintained at temperature suitable for effecting the same type of conversion in each mass, effecting said cycle under conditions such that the quantity of heat stored in said masses during regeneration is in excess of that required for effecting the on-stream reactions, admitting additional and comparatively cool hydrocarbon charge to said stream during its movement between at least one pair of adjacent contact masses to utilize excess stored heat by transferring sensible heat of said stream to said additional charge to heat the latter, constricting said stream at one point in its movement from one mass to the next mass, and effecting the feeding of said additional charge at said point of constriction.

17. In use of contact mass alternately on-stream to effect conversion of a hydrocarbon charge which produces burnable deposit on said mass and in regeneration by burning of said deposit wherein heat required for conversion and supplied by said mass is stored in the latter during said regeneration, the process comprising effecting such a cycle in a plurality of separate contact masses through which a hot stream of said charge passes in succession while being maintained at temperature suitable for effecting the same type of conversion in each mass, effecting said cycle under conditions such that the quantity of heat stored in said masses during regeneration is in excess of that required for effecting the on-stream reactions, admitting additional and

comparatively cool hydrocarbon charge to said stream during its movement between at least one pair of adjacent contact masses to utilize excess stored heat by transferring sensible heat of said stream to said additional charge to heat the latter, constricting said stream at one point in its movement from one mass to the next mass, effecting the feeding of said additional charge at said point of constriction, and withdrawing a portion of said stream after its issuance from a mass and prior to the feeding of additional charge between the masses.

18. In the art of treating hydrocarbon material involving engagement thereof with contact material which is substantially inert catalytically, the process which comprises heating the contact material of a pair of contact zones, to cause such contact material to be in a temperature range which is effective as regards vaporization and viscosity-breaking of heavy hydrocarbon material in the liquid phase while preventing any substantial cracking thereof, at the contact time employed, into lower boiling hydrocarbons of the gasoline type, passing a charge of heavy hydrocarbon material while at least partially in the liquid phase into one contact zone at temperature lower than the temperature of the contact material therein with resultant vaporization and viscosity-breaking of the liquid phase material and production of a vaporized mixture which, at temperature elevated toward that of said last named contact material, enters a mixing zone between said contact zones, and introducing into

15

20

25

30

said mixing zone another charge of heavy hydrocarbon material while at least partially in the liquid phase and having temperature lower than that of said vaporized mixture, heat being exchanged between the hydrocarbon material last named and said vaporized mixture to produce a partially vaporized hydrocarbon mixture having temperature lower than that of the contact material in the other contact zone, said hydrocarbon mixture, as the operation proceeds, passing into said last named contact zone with resultant vaporization and viscosity-breaking of the liquid phase portion thereof.
